CONTROL MECHANISM FOR WELL PUMPS

James Matt West, Fayetteville, Tenn.

Application October 16, 1951, Serial No. 251,574

11 Claims. (Cl. 200—84)

1

The invention relates to control mechanism for well pumps and particularly to mechanism for operating an electrical switch to control a pump. The present arrangement is an improvement upon that disclosed in my prior application S. N. 58,434, filed November 5, 1948, for "Control Mechanism for Well Pump."

The primary object of the invention is to provide a simple yet effective device which will control a pump so as to regulate the level of water.

The device may be used either as a high level or low level control.

In pumping water from wells, it is important that so much water shall not be withdrawn that the water level falls below the pumping barrel, or, in other words, that the well shall not be pumped dry. The present arrangement may be used for cutting off the pump before the level of the water falls below the pumping barrel, and for cutting the pump back on when the water rises above a given level substantially higher than the lower level.

The arrangement may also be used for controlling the water in a sump so as to operate the pump whenever the water reaches a given height, and to keep the pump operating until the water drops to a level substantially lower than its maximum height, so as to prevent an excessive amount of water from accumulating in the sump.

Another object of the invention then is to provide a device of this type which allows a wide range between the water levels at which the pump is turned on and off.

Still a further object of the invention is to provide a device of this type in which the member which moves in response to the water level, which may be a float or a weight, moves through only a short distance as compared to the distance between the two water levels so that the movable switch member has an equally short movement and the whole device can therefore be made small, light in weight and compact. The invention contemplates an arrangement in which the float or weight stays in raised position until the lower water level is reached, then drops a short distance to actuate the switch and turn on or off the pump, and then stays in lowered position until the upper water level is nearly reached, rising thereafter only a short distance to actuate the switch and turn the pump off or on.

An additional object of the invention is to provide a device of this type in which an elongated float or weight is used to control the switch, this float having a vertical movement which is only a small portion of its total length.

In general, the invention provides some means which yieldingly resists downward movement of the float or weight, this means being capable of sustaining a great part of the weight of the float or weight, but not the whole weight, so that when the float is completely or almost completely out

2

of the water it will move downwardly and turn the switch member.

Further objects and advantages of the invention will appear more fully from the following description, especially when taken in conjunction with the accompanying drawings, which form a part thereof.

In the drawings:

Fig. 1 shows a cross section of a hole in which the water level is to be regulated, together with the control mechanism, according to the present invention, in side elevation;

Fig. 2 is a view of the control mechanism from the left hand side of Fig. 1; and

Figs. 3, 4 and 5 are cross sections through the mechanism in different positions during its operation.

The arrangement, as shown in the drawings, is utilized for controlling the level of water in a hole 2, which may be, for example, a well, a sump or the like. The control mechanism includes a base 4, on which are two upstanding plates or ears 6. A pivot 8 extends through and is journaled in these plates and on this is mounted a block 10 of some suitable material. The pivoting movement of block 10 is limited by adjustable stops 12, which are threaded carried by base 4 on opposite sides of pivot 8.

Block 10 carries a generally horizontally extending tube 14, which may be of metal. The greater part of the length of this tube is on one side (right-hand side in Fig. 1) of pivot 8. Members 16 are threaded in each end of the tube, and have on their inner ends cup-shaped portions 18, for receiving a ball 20. On the bottom side of tube 14 are wedge-shaped plates 22, the thicker ends of which are located adjacent cups 18, while the thinner ends are adjacent the longitudinal center of the tube.

40 A flexible member, such as a chain 24, is secured to block 10 on the opposite side of pivot 8 from the greater part of tube 14, and connected to the chain is a weight or float 26.

Pivot 8 is rigid with block 10 and turns in ears 45 6. On the outside of one of the ears, also rigid with pivot 8, is a mercury switch 28, which is connected by wires 30 to a suitable pump 32.

The arrangement above described operates as follows:

50 Assuming that the device is to be used to prevent the level of the water in a well from falling too low, the switch 28 is arranged so as to close and thus to operate the pump when the mechanism is in the position shown in Figs. 1 and 3, and to break the circuit when the mechanism is in the position shown in Fig. 5. Member 26 is of such weight with respect to the weight of member 14 that when the level of the water is such as to submerge any substantial part of the member 26, the tube 14 and ball 20, which under these conditions is at the right-hand end of the tube as

60

shown in Fig. 3, outbalances the member 26 and holds the mechanism in the position shown in Fig. 3, in which, for the purposes of a well pump, switch 28 is closed and the pump operates. However, the weight of member 26 is enough when it is completely out of the water to overbalance member 14 and ball 20, and when the water level drops below the lower end of member 26 it will swing the member 14 to the position shown in Fig. 4. At this point, because of the slope of wedge member 22, the ball will start to roll to the left, and as the weight resisting the movement of member 26 repeatedly decreases because of the decreased leverage exerted by ball 20, the parts will shift rapidly to the position shown in Fig. 5, in which the switch is open and the pump stops operating. Thus, when the level of the water is too low the pump cannot draw any more water from the well.

As the water level rises, the effective weight of member 26 decreases because of the buoyancy of the water, but since ball 20 is at the left-hand end of tube 14 the parts remain in the position shown in Fig. 5 until member 26 is almost entirely submerged. The part 14 is of such weight and is so positioned with respect to the pivot 8 that it will overbalance the pull of the member 26 and chain 24 when member 26 is completely submerged. When this takes place, the members will shift from the position shown in Fig. 5 to that of Fig. 4, and the left-hand wedge 22 will cause the ball to start rolling towards the right. Upon this action, the ball will rapidly complete its travel and will shift the switch 28 quickly to the position shown in Figs. 1 and 3, in which the pump 32 is energized.

For use as a sump pump or the like, switch 28 is reversed, and will close when the parts are in the position shown in Fig. 5 and open when they are in the position of Fig. 1. The shifting of the parts in response to changes in the water level will take place in the same manner as I have described above.

The end positions of the ball 20 can be regulated by turning member 16 to compensate, for example, for variations in the length of chain 24 or for any other needed adjustment.

While I have described herein one embodiment of my invention, I wish it to be understood that I do not intend to limit myself thereby except within the scope of the claims hereto or herein-after appended.

I claim:

1. Well control mechanism comprising a generally horizontal elongated member mounted to turn on a substantially horizontal axis, a mass mounted for movement longitudinally of said member, means carried by said member to limit movement of said mass to a path between a point close to and a point remote from the vertical plane through said axis, means to attach a water-level-responsive element to said member on the other side of the axis from said remote point, and electric circuit making and breaking means operatively connected to said member to be operated by rocking of said member about its axis, the portion of the mechanism on the same side of the axis as the remote point being heavier than the portion on the other side of the axis when the mass is at a point close to the axis.

2. In mechanism as claimed in claim 1, an element connected to said member by said attaching means, said element and the portion of the member on the same side of the axis exerting greater and less leverage respectively about the

axis than the portion of the member on the other side of the axis and the mass when the mass is at the close and remote points respectively.

3. Well control mechanism comprising a support, a substantially horizontal pivot carried by said support, a block mounted to rock on said pivot, a tube carried by said block and extending generally horizontally with its longitudinal axis transverse to the vertical plane of the pivot axis, a mass movable longitudinally within said tube, means to limit movement of said mass to a path between a point close to and a point remote from said vertical plane, means to attach a water-level-responsive member to the said block on the other side of the pivot from said remote point, and electric circuit making and breaking means operatively connected to said block to be operated by rocking of the block about the pivot axis, the portion of the mechanism on the same side of the axis as the remote point being heavier than the portion on the other side of the axis when the mass is at the point close to said vertical plane.

4. Mechanism as claimed in claim 3 in which said mass is a ball.

5. Mechanism as claimed in claim 4 in which said movement limiting means are adjustable longitudinally of the tube.

6. Mechanism as claimed in claim 5, in which said movement limiting means include inwardly directed cup-shaped members adjacent each end of the tube and stems carrying said cup-shaped members and threaded in the ends of the tube.

7. Well control mechanism comprising a support, a substantially horizontal pivot pin mounted to turn in said support, a block rigid with said pin, a tube carried by said block and extending generally horizontally with its longitudinal axis transverse to the vertical plane of the axis of said pin, a mass movable longitudinally within said tube, means to limit movement of said mass to a path between a point close to and a point remote from said vertical plane, means to attach a water-level-responsive member to the said block on the other side of the pivot from said remote point, and a mercury switch rigid with said pin, the portion of the mechanism on the same side of the axis as the remote point being heavier than the portion on the other side of the axis when the mass is at the point close to said vertical plane.

8. Mechanism as claimed in claim 3 in which said mass is a ball, said tube having a bottom surface sloping slightly from points adjacent each end towards the longitudinal center thereof.

9. Mechanism as claimed in claim 8 in which said movement limiting means are adjustable longitudinally of the tube.

10. Mechanism as claimed in claim 9, in which said movement limiting means include inwardly directed cup-shaped members adjacent each end of the tube and stems carrying said cup-shaped members and threaded in the ends of the tube.

11. Mechanism as claimed in claim 10 having adjustable stop means to limit the rocking of said block.

JAMES MATT WEST.
